UNITED STATES PATENT OFFICE.

ELMER E. HAUER, OF SPRINGFIELD, OHIO, ASSIGNOR TO THE LAGONDA MANUFACTURING COMPANY, OF SPRINGFIELD, OHIO, A CORPORATION OF OHIO.

ROTARY MOTOR.

147,238.

Specification of Letters Patent. Patented July 20, 1915.

Application filed December 31, 1913. Serial No. 809,737.

To all whom it may concern:

Be it known that I, ELMER E. HAUER, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors and more particularly to a motor adapted to travel through a tube with a cleaner, although it may be used for other purposes.

The object of my invention is to provide 15 an improved motor simple, strong and efficient that will withstand the shocks and jars incident to its use.

A further object is to so simplify the construction as to reduce the cost and provide 20 a motor that can be easily assembled and readily taken apart.

With these and other objects in view my invention consists of the constructions and combinations hereinafter described and set 25 forth in the claims.

In the accompanying drawings which form a part of this specification Figure 1 is a longitudinal section of a motor embodying my invention; Fig. 2 is a longitudinal 30 section taken on the line 2-2 of Fig. 4; Figs. 3, 4, 5 and 6 are cross-sections on the lines 3-3, 4-4, 5-5 and 6-6 respectively of Fig. 1; Fig. 7 is an end view and Figs. 8 and 9 each show a modification.

35 In the drawings 1 represents a casing of uniform bore open at its respective ends and having a stop intermediate of said ends. The stop may be formed integral with the casing; but in view of the difficulty of always obtaining an accurate bore against the shoulder of an integral flange I may form the stop separately from and secure it to the casing. This can be done in any suitable way; but I preferably form an annular recess in the casing and expand a ring or section of tubing into said recess forming a stop 2 as particularly shown in Figs. 1, 2 and 3. This gives a very strong, substantial and permanent construction to withstand the shocks and jars incident to the use of such motors in driving tube cleaners. A motor bearing member 3 is seated against the front side of said stop and is preferably provided with a bushing 4. The rear end of said member has a flange 5 and a plate

6 is seated between said flange and bushing and said plate is provided with ports 7. A dowel pin 8 secures said plate from rotation. A valve plate 9 having a flange at its inner end is seated in a recess of said plate 6 with 60 said flange extending between said plate and the flange 5 of the bearing member; and said valve plate is secured to the plate 6 by a screw 10. Said valve plate is provided with ports 11 of successively reduced 65 size adapted to register with the ports 7 of the plate 6. It will be seen that by loosening the screw 10 the valve plate can be adjusted so that larger or smaller ports 11 of the valve plate will register with the ports 70 7 of the plate 6 whereby a greater or less amount of the motive agent will be admitted.

A motor cylinder 12 is seated within the casing 1 against the front side of the motor bearing member 3 and is pinned thereto by dowels 13. A motor bearing member 14 is seated within the casing 1 against the front end of the motor cylinder 12 and is pinned thereto by dowels 15 and said member is 80 preferably provided with a bushing 16. A thrust bearing is provided at the rear end of the member 14 and for this purpose an anti-friction bearing is preferably employed. It is seated in a recess of the member 14 and comprises two disks 17, each having oppositely disposed hemispherical recesses opening through the outer walls so that when the disks are riveted together by rivets 18 with the balls 19 in said recesses 90 the balls will project slightly beyond the outside walls of said disks and contact with wear plates 20 thus forming an easy running bearing; and the disks 17 form a holding member for the balls that permanently keep the balls in assembled position so that when the motor is taken apart they will not drop out and be lost. The motor cylinder 12 is provided with a chamber of such dimensions that when the rotary motor member 21 is mounted therein it will contact with the walls of the chamber in two places opposite each other forming two oppositely disposed chambers 22 and 23 as particularly shown in Figs. 4 and 6. Piston blades 24 105 seated in recesses of the rotary motor member are adapted to move radially into the chambers 22 and 23 in a well-known manner. The rotary motor member 21 is provided with a forwardly and rearwardly ex- 110

tending shaft journaled in said bearing members, the front end of said shaft extending beyond the end of the motor and being screw-threaded to attach the tool to be driven. Ports 25 arranged to register with the ports 7 of the plate 6 intersect with cross-ports 26 opening to the motor chamber behind the blades 24 to supply the motive agent for driving the motor.

10 A supply head 27 having an opening 28 to attach a supply conduit is screw-threaded within the casing 1 and tightened against the stop 2 to more securely hold the head in place and the valve plate 9 projects into the 15 opening 28.

An exhaust head 29 having a central tapered opening 30 is screw-threaded into the casing within the opposite end of said casing, said tapered opening contacting a corresponding taper of the bearing member 14, such taper being of an inclination to more securely tighten and hold said member, as well as the cylinder 12 and bearing member 3 in place against the stop 2.

25 The motor cylinder is provided with exhaust ports 31 opening into ports 32 through the member 14 which in turn open into an annular chamber 33 formed between said member and the exhaust head and the motive agent escapes through ports 34 in said head.

It will be noted that the rotary motor member may be first assembled with the motor cylinder and bearing members and then introduced through an end of the casing and secured against the stop by one of said heads; or one of said bearing members and the cylinder may be first pressed in place against the stop and then the rotary motor member and other bearing member may be introduced and secured.

Fig. 8 shows a modification in which the stop 2^a is made integral with the casing 1^a; and Fig. 9 shows another modification in which a stop 2^b is screw-threaded at its rear end to screw-threads 35 that project into the bore of the cylinder 1^b. Said stop is introduced from the front end of the casing and when the screw-threaded portion has engaged the threads 35 of the casing its further rearward movement is prevented by the unthreaded portion of the stop.

Having thus described my invention I claim:—

55 1. In a rotary motor, a casing open at its respective ends and having an inwardly extending stop intermediate of said ends, bearing members and a motor cylinder between said members, said members being introduced through one end of said casing with means to hold the same in place against said stop, a supply head secured to the opposite end of said casing and a rotary motor member in said cylinder journaled in said bearings, substantially as described.

2. In a rotary motor, a casing open at its respective ends and having an inwardly extending stop intermediate of said ends, a cylinder having a motor chamber with bearing members at opposite ends thereof secured against rotation thereto introduced through one end of said casing with means to hold the same in place against said stop, a supply head secured to the opposite end of said casing and a rotary motor member in said chamber journaled in said bearings, substantially as described.

3. In a rotary motor, a casing open at its respective ends and having an inwardly extending stop intermediate of said ends, bearing members and a motor cylinder between said members, said members being introduced through one end of said casing with means to hold the same in place against said stop, a rotary motor member in said cylinder journaled in said bearings, a thrust bearing seated in a recess in one of said bearing members and a supply head secured to the opposite end of said casing, substantially as described.

4. In a rotary motor, a casing open at its respective ends and having an inwardly extending stop intermediate of said ends, bearing members and a motor cylinder between said members, said members being introduced through one end of said casing with means to hold the same in place against said stop, a rotary motor member in said cylinder journaled in said bearings, a thrust bearing seated in a recess of one of said bearing members, said thrust bearing having balls and a holding member therefor arranged to permanently hold said balls in assembled position, substantially as described.

5. In a rotary motor, a casing open at its respective ends and having an inwardly extending stop intermediate of said ends, bearing members and a motor cylinder between said members, said members being introduced through one end of said casing with means to hold the same in place against said stop, a rotary motor member in said cylinder journaled in said bearing, a thrust bearing seated in a recess of one of said bearing members, said thrust bearing having balls and a holding member therefor arranged to permanently hold said balls in assembled position and wear plates on opposite sides of said holding member, substantially as described.

6. In a rotary motor, a casing having an open end, a journal bearing member introduced through said open end, means to limit the inward movement of said member, said member being tapered toward its outer end and a head screw-threaded to said casing and having a tapered opening to engage the taper of said member, substantially as described.

7. In a rotary motor, a casing having an

- open end, a journal bearing member introduced through said open end, means to limit the inward movement of said member, said member being tapered toward its outer end, 5 a head screw-threaded to said casing and having a tapered opening to engage the taper of said member, said member and head having ports therethrough and an intermediate annular chamber formed by said member and head, substantially as described.
8. In a rotary motor, a casing open at its respective ends and having an inwardly extending stop intermediate its ends, a cylinder forming a motor chamber and having 10 journal bearing members at its opposite ends, one of said members being seated against said stop and the other being tapered at its outer end, a head screw-threaded to one end of said casing and having a 15 tapered opening to engage the taper of said tapered bearing to clamp and hold said cylinder and bearings in place against said stop, said tapered bearing and head each having exhaust ports therethrough, a rotary 20 motor member in said chamber journaled in said bearings, a head at the opposite end of said casing with means to supply the motive agent to said motor chamber, substantially 25 as described.
9. In a rotary motor, a casing open at its respective ends and having an inwardly extending stop intermediate said ends, a cylinder having a motor chamber with bearing members at opposite ends thereof secured 30 against rotation thereto, introduced through one end of said casing with means to hold the same in place against said stop, a rotary motor member with radially moving blades 35 in said chamber and having a shaft projecting forwardly and rearwardly therefrom journalled in said bearings, a ported member secured to the rear bearing member having 40 ports adapted to register with ports in said shaft and rotary motor member opening to the motor chamber and a head adapted to attach a supply conduit, substantially as described.
10. In a rotary motor, a casing open at its respective ends, a stop intermediate of said ends, said openings being of uniform diameter on opposite sides of said stop, a rotary motor member with bearings therefor, detachable heads secured within the respective ends of said casing, one of said heads securing said bearings within said casing 50 against said stop and the other head being adapted to attach a supply conduit, substantially as described.
11. In a rotary motor, a casing open at its respective ends, a stop intermediate of said ends, a rotary motor member and bearing members therefor with means to secure said bearing members within the casing against said stop, a supply head screw-threaded to the casing against the other side of said 55 stop, one of said bearing members having a valve seated therein and projecting into the supply opening in said head, substantially as described.
12. In a rotary motor, a casing having an open bore throughout its length with an annular recess, a section of tubing expanded into said recess and projecting into said bore forming a stop, a rotary motor member and bearings therefor with means to secure the same within the casing against said stop, substantially as described.

In testimony whereof I have hereunto affixed my signature in the presence of two witnesses.
